UNITED STATES PATENT OFFICE.

WILLIAM GORMAN, OF NEW BRITAIN, CONNECTICUT, ASSIGNOR TO RUSSELL AND ERWIN MANUFACTURING COMPANY, OF SAME PLACE.

DESIGN FOR A LETTER-BOX PLATE.

Specification forming part of Design No. 5,961, dated June 25, 1872.

Specification describing a Design for a Letter-Box Plate, invented by WILLIAM GORMAN, of New Britain, in the county of Hartford and State of Connecticut.

The nature of my design is fully represented in the accompanying photographic illustration, to which reference is made.

A represents the plate proper, the contour of which consists of straight lines running at different angles and thereby forming a point at the center of both sides and ends, as shown. In the middle of the plate A is an oval hole, B, back of which is a hinged plate, C. The ornamentation of the plate A consists of a

plain ledge around its edge and the edge of the hole B. The space inclosed by said ledges is ornamented with raised ornamental work. The plate C has a raised ledge near its edge, inside of which, in relief, is the word "Letters."

I claim as my invention—

1. The design for the contour of the plate A, substantially as shown.
2. The design for the plate C, substantially as shown.

WILLIAM GORMAN.
